UNITED STATES PATENT OFFICE.

JULIAN ALEXANDER, OF PHILADELPHIA, PENNSYLVANIA.

STRETCHING MECHANISM.

1,115,269.

Specification of Letters Patent.

Patented Oct. 27, 1914.

Application filed April 29, 1914. Serial No. 835,246.

To all whom it may concern:

Be it known that I, JULIAN ALEXANDER, a citizen of the United States, residing in Philadelphia, Pennsylvania, have invented 5 certain improvements in Stretching Mechanism, of which the following is a specification.

With the devices heretofore used for stretching leather for use in the manufacture of driving belts it has been found difficult or impossible to properly clamp and stretch irregularly shaped strips or butts without injuring them in such manner as to render comparatively large pieces practically valueless and one object of the present 15 invention is to provide a device of the above class which under conditions of use shall properly perform its functions without injuring any but relatively small amounts of the material operated upon.

Further objects of the invention are the provision of a stretching device which shall be durable, quickly and conveniently adjustable to suit it for attachment to pieces 25 of widely varying shapes and which shall so hold such pieces that they may be properly dried.

These objects and other advantageous ends I attain as hereinafter set forth, reference 30 being had to the accompanying drawings in which,

Figure 1 is a side elevation of a stretching device embodying my invention; Fig. 2 is a plan view of Fig. 1; Figs. 3 and 4 are enlarged sectional views taken respectively on the lines *a—a* and *b—b* Fig. 2; Figs. 5 to 35 10 inclusive are fragmentary views on an enlarged scale, illustrating details of the invention; and Fig. 11 is a diagrammatic view.

In the above drawings, 1 is a table or supporting structure preferably made in the form of a metallic frame work and carrying a slidable beam 2 provided on its lower face with a toothed-rack 3 and having adjacent 45 one end a standard 2^a, the rack being engaged by a gear wheel 4, by which said beam may be moved in either of two directions longitudinally of the table. The table 1 is provided with brackets 5; each having a pocket 6, for a purpose hereafter noted. Standards 7 are secured to the table 1 and extend upwardly from the top thereof, as shown in Fig. 1; being connected by a cross bar 7^a.

55 A frame 8, consisting in the present instance of two long cylindrical bars 9 and 10

connected adjacent their ends by two transverse cylindrical bars 11 and 12, has its bars 9 and 10 supported on the cross bar 7^a and its bar 11 resting within the pockets 6 of the brackets 5. This latter bar 11 forms a slide-way for a slide or carriage 13, which rests thereon. A hook bolt 14 (Fig. 3) extends under the bar 11 and projects upwardly through said carriage; its upper end being 65 threaded for the reception of a nut 17 whereby a cam 15 mounted on said bolt is retained in position. Said cam has a radially projecting handle 16. The bolt 14 also provides a pivotal support for two clamps 18 and 19, each consisting of two pairs of plates 24—25 and 26—27 pivotally mounted on said bolt and respectively fixed to bars or jaws 20, 21 and 22, 23, preferably of rectangular cross section. The jaws are 70 provided with teeth 29 for biting into any material clamped between them.

Two other hook bolts 30 and 31 have their hooked ends extending under the bars 9 and 10 respectively and pass through carriages 80 35 which slidably engage said bars. The bolt 31 in addition serves as a pivotal support for two bearings 36 and 37 slidably engaged by the jaws 20 and 21 respectively and with them normally held apart by a coil 85 spring 38, as shown in Figs. 7 and 8.

The bearing 36 has on its upper face a cam 39 formed to coöperate with a cam 40 pivotally mounted on the bolt 31 and held in place by a nut threaded thereon. With 90 this construction the turning of the cam 40 in one direction will cause the cam 39 to depress the bearing 36 and thereby move the jaw 20 toward the jaw 21 against the action of the spring 38. The cam 40 is provided 95 with an operating handle or lever 41 and obviously its operation in moving the jaws together also causes the hooked end of the bolt 31 and the carriage 35 to clamp the bar 10 of the frame 8. The bearings 36 and 100 37 have extensions 42 and 43 which act as stops to prevent the jamming or too close approach of the jaws 20 and 21 and also balance the pressure exerted on the jaws 20 and 22 to prevent the bending of the bolts 105 30 and 31. The stops 42^a and 43^a also perform the same function for the bolt 14. Similarly the bolt 30 has pivotally mounted on it two bearings 44 and 45 which form sliding supports for the jaws 22 and 23; the bearing 45 resting on the carriage 35 and the bearing 44 having on its upper face a

cam 46. This latter coöperates with a cam 47 pivotally mounted on the bolt 30 and having a handle 49. A spring 48 similar to the spring 38 tends to separate the bearings 44 and 45 and maintain the jaws 22 and 23 out of contact with each other.

A spring 50 on the hook bolt 14 tends to keep the plates 25 and 26 separated and thus aids the springs 38 and 48 in normally keeping the jaws 20, 21 and 22, 23 apart. The cam 15 coöperates with a cam 51 between itself and the plate 24, so that when it is turned in one direction, the plates 24 and 26 will be actuated to respectively move the jaws 20 and 22 toward the jaws 21 and 23.

With the above combination, when the cams 40, 47 and 52 are in their released positions, the bolts 14, 30 and 31 may be easily moved upon the bars of the frame 8 which they engage. When however any of these cams are turned to move the jaws into clamping engagement with any material there will be a simultaneous clamping action of their hooked ends and of the carriages 25 upon the bars of the frame 8.

At the opposite end of the frame from the jaws 18 and 19 I provide a clamp 54 having a lower jaw 55 extending across the frame 8 and slidably mounted on the bars 9 and 10 thereof. An upper jaw 56 is adjustably mounted on bolts 57 carried by the lower jaw and is normally held away from the same by springs 59. Each bolt 57 has a cam 60 rotatably mounted upon its upper end 35 and these cams coöperate with cams 61 on the upper jaw 56, so that when they are turned in one direction the jaws 56 will be moved toward the jaws 55 against the action of the springs 59. The cams 60 have 40 handles 62 to facilitate their turning, and each bolt 57 has a nut 63 on its upper end. The upper jaw 56 has upwardly projecting extensions 64 which have depressions or recesses respectively in line with the recesses 45 of the extensions 34 of the nuts 33 and said parts are so arranged that their recesses may receive the frame 8 of other stretching devices similar to that above described.

In order to hold the clamp 54 in any given 50 position I fix to the bars 9 and 10 of the frame 8 two toothed racks 66 and at each end of the lower jaw 55 I mount a pawl 65 in position to coöperate with said racks. These pawls are provided with handles 68 55 whereby they may be withdrawn from engagement with the racks when it is desired to slide the clamp 54 along the bars 9 and 10. For laterally stretching the material engaged by the other clamps I provide a 60 clamp 69 which extends transversely across the frame 8 and consists of a tube 70 having a tapped head 71 through which extends a threaded clamp rod 72. Said head 71 has teeth 73 formed in its upper face in position to coöperate with teeth 74 on a clamp-

ing jaw 75 held to the head by a bolt 76. A rod 77, is mounted to freely slide within the tube 70, and has on one end a head 78 to which a jaw 81 is adjustably connected by a bolt 82, the adjacent faces of the head and jaw being provided with teeth 79 and 80 as shown in Fig. 4.

In using my invention one end of a leather strip or butt, usually cut off substantially at right angles to the long edges thereof, is inserted 75 between the upper and lower jaws of the clamp 54 and the cams 60 are turned so as to move downwardly the upper jaw 56 thereby causing it to grip said strip. The bars 14, 30 and 31, together with the elements 80 supported thereby are then slid along their respective bars of the frame 8 until the jaws 20, 21 and 22, 23 are in positions adjacent and practically parallel with the irregular end portions of the strip to be stretched as 85 shown in Figs. 2 and 3, and said portions are inserted within said jaws. The cams 40, 47 and 52 are then turned thus causing the jaws of the clamps 18 and 19 to grip the strip. The long edges of the leather are 90 then clamped between the heads 71 and 78 and their coöoperating jaws 75 and 81 of the stretching clamp 69 as shown in Fig. 4. The frame having the leather strip secured to it as above described is then placed upon 95 the table 1 so that the inner face of the lower jaw 55 abuts upon the standards 7 and the bar 11 is engaged by the standard or projection 2^a on the stretching beam 2. By means of the gear wheel 4 the beam 2 and 100 with it the frame 8 is moved in the direction shown by the arrow Fig. 1, although the clamp 54 will remain stationary since the pawls 65 are so mounted as to slide over the teeth of the racks 66. As a consequence 105 the leather strip is longitudinally stretched and after it has been subjected to sufficient tension the pawls 65 by engaging the teeth of the racks 66 retain it in this condition. By rotating the gear wheel 4 in a direction 110 opposite to that first indicated the beam 2 is moved in an opposite direction and the frame with the leather strip in a stretched condition may be removed from the table. Any buckling or other irregularities in the 115 surface of the leather strip may be removed by turning the threaded bar 72 of the stretching clamp 69 so as to move apart the heads 71 and 78 with their associated parts and this may be done either prior to the removal 120 of the frame from the table or during the longitudinal stretching of the strip.

Instead of having but one set of the pivotal clamps 18 and 19 on the frame as illustrated, I may employ two or more such 125 sets all operated in substantially the same manner. For example, instead of having the straight cross clamp 54 at one end of the frame I may have an additional set of clamps 18 and 19, in which case the bar 12 130

could be employed as a slideway for the rod 14 and the slide or carriage 13. Also, instead of having two clamps pivoted together I may have three or more sets pivoted together in link formation. In this latter case I could follow more closely the irregular edge of the leather, since the clamping jaws could be made relatively short and kept close to the irregular edge of the leather strip.

The value of my invention for stretching strips or butts of leather will be obvious from an inspection of Fig. 11, since if the ordinary straight clamps were employed to grip both ends of the leather strip shown therein, it would be necessary to cut off a large piece α of triangular shape from the left hand end since such clamps would make transverse grooves $y-y'$ and $z-z'$ and only 20 the part of the leather strip between such grooves could be used for the belt strips. With my invention, instead of having the mark of the clamp, which is near the irregular end, extending directly across the leather as at $y-y'$, it will closely follow the irregular edge as shown by the lines A and B, Fig. 11, so that comparatively little of the leather will have to be cut away since all the leather between the line $z-z'$ and the lines 30 A-B is available for use. By having the teeth of the clamps in the form of long ridges and by having the frame 8 open between the bars 9, 10, 11 and 12, air will have free access to all parts of the leather strip 35 with the exception of the small portion which is held between the teeth of the clamps. This is a very important feature, especially in the case of belt leather for it is important that all portions should dry 40 evenly and at the same time.

I claim:

1. The combination in a stretching device of a supporting structure; a plurality of angularly adjustable jaw clamps thereon; 45 means for pivotally connecting the jaws of each clamp; and a single device for simultaneously actuating the jaws and causing them to be rigidly held to the supporting structure.

2. The combination of a supporting structure; a plurality of pivotally connected sets of clamping jaws; means slidable on said structure and formed to constitute a sliding bearing for the clamping jaws; with mechanism for securing said jaw bearing to the supporting structure.

3. The combination in a stretching device of a supporting structure having guideways; a plurality of clamps; means pivotally connecting the clamps and adjustably securing them to certain of said guideways; and bearings for said clamps adjustably secured to the other of said guideways.

4. The combination in a stretching device 65 of a supporting structure having guideways;

a plurality of clamps; means for pivotally connecting the clamps and adjustably securing them to certain of said guideways; and bearings adjustably mounted on others of said guideways; the clamps having jaws 70 slidable in said bearings.

5. The combination in a stretching device of a clamp having a threaded opening and a tube communicating therewith; a second clamp; a member having a portion slidable 75 within said tube and secured to said second clamp; with a threaded rod entering said threaded opening and contacting with said member to move the clamps apart.

6. The combination in a stretching device 80 of a supporting structure; a plurality of clamps each having longitudinally extending jaws; means pivotally connecting the clamps and slidably engaging the supporting structure; with bearing members slidably engaging the supporting structure and each having a slideway for the jaws of a 85 clamp.

7. The combination in a stretching device of a frame consisting of a number of bars 90 joined together; a plurality of clamps; means pivotally connecting said clamps and slidably securing them to one of said bars; pivot members slidably secured to others of said bars; with bearing members pivotally 95 mounted on said pivot members, and each forming a slideway for a clamp.

8. The combination in a stretching device of a supporting structure; a plurality of clamps having jaws; means for pivotally 100 connecting the clamps; with common means for moving the jaws together and securing the clamps to the supporting structure.

9. The combination in a stretching device of a supporting structure; a plurality of 105 clamps having jaws; means for pivotally connecting the clamps; means for normally holding the jaws apart; with common means for moving the jaws together and securing them to the supporting structure.

10. The combination in a stretching device of a supporting structure; a plurality of 110 clamps; members slidable on said structure and supporting said clamps; means pivotally connecting the clamps and secured to certain of said 115 slidable members; and means for adjustably securing the members to the supporting structure.

11. The combination in a stretching device of a frame consisting of bars secured 120 together; a plurality of jaw clamps; carriages slidable on said bars; a bolt forming a pivotal connection for the clamps and engaging one of said frame bars; means on said bolt for securing it to said frame bar and for moving together the jaws of the clamps; bearing members forming slideways for the jaws of the clamps; bolts extending through said bearing members and engaging the bars of the frame; and means on said 125 130

4
latter bolts for securing them to the bars of the frame and for moving the jaws together.

12. The combination in a stretching device of a frame consisting of bars secured together; a plurality of jaw clamps; carriages slideable on said bars; a bolt forming a pivotal connection for the clamps and engaging one of said frame bars; means on said bolt for securing it to said frame bar and for moving together the jaws of the clamps; bearing members forming slideways for the jaws of the clamps; bolts extending through said bearing members and engaging the bars of said frame; means on said latter bolts for securing them to the bars of the frame and for moving the jaws together; and springs on the bolts for normally keeping the clamp jaws apart.

13. The combination in a stretching device of a frame; a plurality of clamps having relatively movable jaws; carriages slideable on said frame and supporting the clamps; a bolt pivotally connecting said clamps and engaging the frame; bearing members forming slideways for the clamps;

pivot bolts extending through said members and engaging the frame; cams on said clamps; and cams on said pivot bolts placed to coöperate with the cams on the clamps to cause movement of the clamp jaws toward each other.

14. The combination in a stretching device of a frame; a plurality of jaw clamps; carriages slideable on said frame and supporting the clamps; a bolt pivotally connecting the clamps and engaging the frame; bearing members forming slideways for the clamps; pivot bolts extending through said members and engaging the frame; cams on said bolts operable to move the clamp jaws together; and means on said bolts for gripping the frame when the cams are operated to move said clamp jaws together.

In testimony whereof, I have signed my name to this specification, in the presence of two subscribing witnesses.

JULIAN ALEXANDER.
